(57) **CLAIM**

The ornamental design for a headset, as shown and described.

DESCRIPTION

FIG. 1 is a rear perspective view of a headset showing environmental features;

FIG. 2 is a front perspective view of the headset of FIG. 1;

FIG. 3 is a right side view of the headset of FIG. 1;

FIG. 4 is a front view of the headset of FIG. 1;

FIG. 5 is a left side view of the headset of FIG. 1;

FIG. 6 is a rear view of the headset of FIG. 1;

FIG. 7 is a top view of the headset of FIG. 1; and,

FIG. 8 is a bottom view of the headset of FIG. 1.

The portions of the headset shown in dashed lines do not form part of the design.
